CLAIM

The ornamental design for a potato patty, substantially as shown and described.

DESCRIPTION

FIG. 1 is a front elevational view of a potato patty, showing our new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a rear elevational view thereof; and

FIG. 7 is a cross-sectional view thereof, taken on the line 7—7 FIG. 1.
